(57) **CLAIM**

The ornamental design for a wireless communication device, as shown and described.

DESCRIPTION

FIG. 1 is a front, top, right-side perspective view of the wireless communication device;

FIG. 2 is a front, bottom, left-side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof; and,

FIG. 8 is a left-side elevational view thereof.

The broken lines depict unclaimed parts of the wireless communication device, and thus form no part of the claimed design.
